2 SHEETS—SHEET 2.

Inventor
S.R. Burke

By *J. Randolph* Attorney

UNITED STATES PATENT OFFICE.

STEPHEN R. BURKE, OF SAN FRANCISCO, CALIFORNIA.

SIGNAL ATTACHMENT FOR FLASH LIGHTS.

Application filed June 6, 1921. Serial No. 475,525.

To all whom it may concern:

Be it known that I, STEPHEN R. BURKE, a citizen of the United States, residing at San Francisco, in the county of San Francisco and State of California, have invented certain new and useful Improvements in a Signal Attachment for Flash Lights; and I do hereby declare the following to be a full, clear, and exact description of the invention, 10 such as will enable others skilled in the art to which it appertains to make and use the same.

This invention has relation to certain new and useful improvements in signals and has 15 for its primary object the provision of an attachment which may be readily applied to a flashlight to convert the same into an electric signal device.

The invention has for another object the 20 provision of a signal attachment of the character stated which will be especially adapted for use in theaters and other places to indicate to parties at a distance the number of vacant seats and the location thereof and to 25 direct the parties desiring such seats to the proper location in the theater.

The invention has for a further object the 30 provision of a signal attachment of the character stated which will be of extremely simple construction, highly efficient in use and which may be readily manufactured at a small cost and applied to the ordinary hand flashlight now in general use.

The invention has for a still further object 35 the provision of a signal attachment of the character stated which will be composed of the minimum number of parts, which may be readily assembled and clamped upon the flashlight and which will operate upon manipulation of the flashlight.

The invention has for still another object the provision of a signal attachment of the character stated in which the outer cylindrical casing may be provided with a transparent 40 plate in a side opening thereof to disclose one of the numbers on the rotatable inner casing and which rotatable inner casing may also be provided with openings in its opposite ends and a hinged closure plate 45 for the opening at the outer end of the inner cylinder, whereby the full benefit of the rays of light from the bulb of the flashlight may be utilized to direct the parties to the vacant seats, by swinging the closure plate to opened 50 position.

The invention has for a still further object, the provision of a signal attachment of the character stated in which the inner casing may be readily secured in or removed from the outer casing or rotated within said outer casing to bring the different numbers before the opening of said outer casing. 60

A still further object of the invention resides in the provision of a flashlight signal which will be of simple construction and 65 operation and in which an outer casing may be located at the bulb end of the flashlight and an inner casing rotatably mounted in the outer casing to bring numbers or other characters thereon in front of an opening 70 of the outer casing, and a cover for the inner casing which may be readily opened or closed, as desired.

The invention has for still another object the provision of a signal attachment of the 75 character stated which will be constructed in such a manner that it may be readily clamped upon or removed from a flashlight of conventional form, as desired.

With the foregoing and other objects in view, as will appear as the description proceeds, the invention consists in the novel construction, combination and arrangement of cooperating elements as hereinafter more specifically set forth, claimed, and shown in 80 the accompanying drawings forming a part of the present application and in which:

Figure 1 is an elevation of a conventional form of flashlight with my signal attachment 85 applied thereto.

Figure 2 is an end view thereof with the closure plate in opened position.

Figure 3 is an enlarged longitudinal section through the signal attachment, a portion 90 of the flashlight being shown in elevation.

Figure 4 is a transverse section on the plane indicated by the line 4-4 of Figure 1, on a slightly enlarged scale.

Figure 5 is a detail view in end elevation 100 of the signalling attachment, looking at the inner or clamp carrying end thereof.

Figure 6 is a view in side elevation of a modified form of the invention.

Figure 7 is a vertical sectional view of 105 the modified form of the invention.

Figure 8 is a detail view in side elevation of the inner casing of the modified form, and

Figure 9 is a detail view in end elevation 110 of said inner casing.

Referring more in detail to the drawings, in which similar reference characters designate corresponding parts throughout the several views, 1 designates in general a flashlight of conventional form upon which the signal attachment 2 is applied.

The signal attachment comprises a relatively stationary outer cylindrical casing 3 having a plurality of inwardly extending converging attaching arms 4 connected at their inner ends to the transversely split clamping ring 5. The extremities of the ring 5 are bent outwardly to form ears 6 which are perforated and through which 15 the clamping screw 7 is extended. One ear 6 is increased in thickness and has its opening threaded to receive the clamping screw 7 so that turning of the screw 7 in one direction will draw the ears 6 together and 20 tighten the clamping ring 5 around the flashlight 1 to securely hold the signal attachment upon the flashlight 1. An opening 8 is formed in the inner end of the outer casing 3 to receive the lens 9 of the flashlight 1, as shown in Figure 3. The outer end of the casing 3 is open to permit the insertion and removal of an inner cylindrical casing 10 which is adapted to be turned with respect to the casing 3 for the 25 purpose hereinafter fully set forth.

The casing 3 has a side opening 11. It also has clamps 12 at the side edges of the opening 11 to receive the edges of a transparent panel 13 formed of mica or the like 35 and which may be applied over the opening 11 from the outer end of the casing 3, as will be readily understood by referring to the drawings. It will also be evident that the clamps 12 may be of any form other 40 than that shown.

The inner casing 10 is formed of a suitable material such as a light metal, as is also the outer casing 3. The inner casing 10 has a plurality of characters, such as the numerals 1, 2, 3 and 4 cut in the lateral wall thereof and adapted to be brought respectively into position opposite the transparent plate 13 so that the light rays from the bulb of the flashlight 1 may pass there-through and thereby render visible the numeral opposite the panel 13. These numerals or other characters are designated by the reference character 14, and it will be evident that the characters may be formed in 55 any suitable and well known manner. The inner casing 10 is preferably provided at its outer end with a flange 15 which rests against the outer edge of the outer casing 3. The inner casing 10 is also provided in its 60 outer end with an opening 16 which is normally closed by a plate 16' pivoted upon the outer end of the inner casing 10, adjacent the opening 15, and preferably at a point above the numeral 4, as shown in the drawings. This closure plate is adapted to swing

upon the pivot pin 17 provided therefor and has a tongue 18 bent upwardly therefrom at a point diametrically opposite to the pivot pin 17, so that the closure plate 16 may be readily turned to closed or opened position, 70 as desired. It will be evident that when the closure plate 16' is swung into opened position, and when the switch button 1' is in position to complete a circuit through the bulb of the flashlight, the rays of light from the bulb will pass out of the end of the signal attachment as well as through the perforated character opposite the transparent plate 13, so that the light rays may be directed to the vacant seats or to any other point desired.

The inner casing 10 has a plurality of relatively spaced fingers 19 projecting from the inner edge thereof and provided with a transverse groove 20 to receive the inwardly pressed annular rib 21 within the casing 3. It will be understood that the fingers 19 also have their free extremities turned slightly toward one another, as shown at 22, so as to permit these fingers to pass over the rib 21 and spring back into position against the same as the ends of the fingers are forced past the rib 21 during insertion of the casing 10 into the casing 3. It will therefore be seen that the flange 15 and fingers 19 will serve to retain the inner casing 10 in proper position for rotation with respect to the outer casing 3, but will at the same time permit of ready withdrawal of the inner cylindrical casing 10, when desired. The flange 15 is milled as shown in Figure 6 to permit it to be used for turning the inner cylinder 10 with respect to the outer cylinder 3.

A modified form of the invention is shown 105 in Figures 6, 7, 8 and 9. The differences between this form and the form shown in Figures 1 to 5 reside in connecting the signal attachment to the flashlight permanently instead of detachably, and this is done by means of an inwardly tapering flange 4^a formed integrally with the flashlight casing 1 and the casing 3, and in connecting the closure plate 16' to the inner casing 3 by a hinge 7^a instead of by a pivot. The hinge 110 7^a is provided with a finger piece 7^b to permit the closure plate 16' to be readily opened, and this plate is normally retained in closed position by a spring 7^c.

From the foregoing description taken in 120 connection with the accompanying drawings, it will be evident that this device may be especially adapted for use by ushers or the like in theaters to signal to a party at the rear of the theater the number, and 125 approximate location of vacant seats and then assist the parties desiring the seats in locating them. It is believed that further detail description of the construction and operation or use of the device will be un- 130

necessary. It is to be understood, however, that while the preferred embodiment of the invention has been shown and described, minor changes in the details of construction and arrangement of parts may be resorted to within the scope of the appended claims without departing from the spirit of the invention.

What is claimed is:—

- 10 1. A signaling attachment for a flashlight comprising the combination with the flashlight casing, of an outer end casing extended from the above end of said flashlight casing, said end casing having a display opening and an open outer end, a display opening rotatably mounted in said end casing and projecting from the open end thereof, said inner casing having characters thereon for display before the side opening of said end casing, 15 said inner casing having an annular flange projecting past the sides of the end casing to provide means for rotating said inner casing, said inner casing having an open outer end, a hinge cover for said open outer 20 end of the casing, and means for swinging said cover to open position.
2. A signal attachment for a flashlight consisting of a casing adapted to be illuminated by the flashlight and resting on the adjacent end wall of the flashlight, said casing having an opening in its base into which the bull's eye of the flashlight extends, a second casing on and movable relatively to the first casing, the casings having signal means for 35 cooperation through movement of the second

casing, clamp means engageable with the flashlight at a distance from the said end wall, and attaching arms for said clamp means on the casing and projecting beyond said base.

3. A signal attachment for a flashlight consisting of an outer casing for mounting on and illumination by a flashlight, an inner casing movable axially of the outer casing, said outer casing having an opening, 45 the inner casing having signal means for display at said opening, and an operating flange at the outer end of the inner casing extending outwardly and overlapping the outer end of the outer casing.

4. A signal attachment for a flashlight consisting of an outer casing for mounting on and illumination by the flashlight, an inner casing movable axially of the outer casing, said outer casing having an opening, 55 the inner casing having signal means for display at said opening, and an operating flange at the outer end of the inner casing extending outwardly and overlapping the outer end of the outer casing, the outer 60 casing having a rib interiorly thereof, and the inner casing having a retaining finger cooperating with said rib.

In testimony whereof I affix my signature in presence of two witnesses.

STEPHEN R. BURKE.
